Joseph A. Torkin,
ATTORNEY.

UNITED STATES PATENT OFFICE.

ANDREW F. LARSON, OF PORTLAND, OREGON, ASSIGNOR TO THE GRAVITY DOOR HANGER COMPANY, A CORPORATION OF OREGON.

SLIDING-DOOR HANGER.

1,375,915.

Specification of Letters Patent. Patented Apr. 26, 1921.

Application filed July 25, 1917. Serial No. 182,620.

To all whom it may concern:

Be it known that I, ANDREW F. LARSON, a citizen of the United States of America, residing at Portland, in the county of Multnomah, in the State of Oregon, have invented certain new and useful Improvements in Sliding-Door Hangers, of which the following is a specification, reference being had to the accompanying drawings.

10 In conformity to established precedent, my invention is referred by title to the class of sliding door hangers, and that despite the fact that my device is adapted to support a door from below as well as from 15 above, and despite the further fact that the door is pendulous and may be described only, if at all, as sliding, in the sense that it has a transverse movement in its opening and closing operations.

20 The precedent referred to is found in the classification of the door hanger shown and described in United States Letters Patent No. 331,258, issued November 24, 1885, to Charles C. Runyan, and of that shown in 25 United States Letters Patent No. 275,852, issued April 17, 1883, to Edwin Prescott. There is no more than a class resemblance between my device and those described in said patents, respectively, inasmuch as their 30 several structures and principles of operation are restricted to certain objectionable limitations which it is one of the objects of my invention to eliminate. Those patents are, nevertheless, believed to afford a 35 concrete showing of the prior state of the art upon which my present invention is predicated.

The objects of my invention and the 40 means whereby they are attained will be better understood, it is believed, from the following specification in view of the prior state of the art as above set forth, than from any general preliminary description that can be offered. Suffice it to say in the 45 present connection that those objects, generally, embrace economy of manufacture through reduction of the weight of metal necessary to be employed in my hanger; the making of it possible to apply my 50 hanger to one half of a door either above or below its medial line, as the case may be, whereby the operation of the door is facilitated, in consequence of the disposition of its center of gravity so obtained; means 55 for causing the door to move throughout its

travel in a substantially true straight line; means for effecting inclination of said straight line, whereby the door may be made retroactive solely by gravity; means for minimizing the pivotal points of suspension of the preponderant weight of a door at every point of its travel, whereby its operation is much facilitated; and door supporting mechanism of the type described, confined wholly within the superficial area 60 of the door at every point of its travel.

My invention is applicable generally to any door of the kind described, but particularly to heavy doors, such, for example, as those used in partition walls to prevent 70 spread of conflagration, commonly called fire doors, and doors for railroad box-cars. In the drawings my invention is shown as applied, for example, to a box-car.

What constitutes my invention will be 75 hereinafter specified in detail and succinctly set forth in the appended claims.

In the accompanying drawings,

Figure I shows only one half of a car door divided horizontally and my hanger 80 in two positions, indicated, respectively, by full and dotted lines, and so much of a car-body as is necessary to be shown in order to illustrate the relationship between the same, the door, and the hanger. It may 85 be here stated that the same supporting mechanism may be, without any change in the mechanism itself, applied to support a door from above or from below. All of the drawings may be, therefore, read accordingly by merely reversing the sheet before the eye of the reader, it being deemed, for that reason, superfluous to multiply the drawings in order to show in separate figures the two modes of application of my 90 device.

Fig. II is an edge view of the subject matter of Fig. I, looking from left to right.

Fig. III is a view similar to Fig. I, but 100 showing application of the hanger to a door in such manner as to render the door self-closing.

Fig. IV is a view of the same corresponding to Fig. II.

Fig. V is a view similar to Fig. I showing 105 my invention in a slightly modified form of embodiment.

Fig. VI is a view of the same corresponding to Fig. II.

Referring to the numerals on the draw- 110

ings, 1 indicates a supporting-frame-piece of a box-car, which, extending across the doorway thereof, constitutes its lintel, the locations of the opposite sides of the doorway being indicated by the numerals 2 and 3. When the drawing is read up-side-down, as it has been specified it may be, the lintel in such case, of course, becomes the threshold. That being understood it avoids confusion to designate the member 1 as above.

4 indicates a door which may be of any suitable and preferred dimensions, material and construction. It is, for emphasis, repeated that my invention is peculiarly applicable to a heavy door with the effect of rendering it, despite its weight, easily movable, with equal facility, at every point of its travel.

The door is by aid of my invention pendulously carried upon the supporting-frame-piece 1, whether the said member be disposed above or below the door. The support of the door upon the member 1 is obtained mainly through the instrumentality of two pairs of reflexed door-supporting members, namely, a pair of links 5 and 6 and a pair of bars 7 and 8, the link 5 being pivotally united as indicated, at the point of reflexion 9, to its bar 7, and the link 6 being in like manner united, as indicated at 10, to its bar 8, the links 5 and 6 being pivotally united by any suitable mechanism at separate points 11 and 12 to the door 4, and the bars in like manner united at separate points 15 and 16, respectively, to the supporting-member 1. It is a distinctive feature of my invention not only that two separate points 11 and 12 are provided for the links 5 and 6, but also that the distance between the respective centers 40 of the pivots or pivot points 11 and 12 is unequal to that between those of the pivots or pivot points indicated at 15 and 16.

The bars 7 and 8 are illustrated in Figs. I and III as angular or deflected lengthwise from a straight line. Such angularity, in one or both bars, is, for some purposes, a preferred construction, for one reason that it is desirable under certain conditions to restrict the field necessary to the operation 50 of the device, but that construction is not essential as will be apparent from consideration of Fig. V, for example.

The pivot mechanism at points 11-12 and 15-16, respectively, may be applied immediately to the door and to the member 1, but, for convenience of application and in order to avoid the necessity of determining their individual location with each application, the points 11 and 12 are preferably 60 disposed in fixed relationship to each other as upon a plate 17, and the points 15 and 16 are, in like manner and for like reason, disposed upon a plate 18. By this contrivance it is necessary, in practice, only to determine with approximate accuracy two points of

location for the plates, instead of precisely fixing the several locations of the four points 11, 12, 15 and 16. When the plates 17 and 18 are used, screws or bolts 19 may be used to secure the plate 17 to the door, and screws 70 or bolts 20 to secure the plate 18 to the supporting-member 1. The plate 17 is, for reasons which will be hereinafter explained, preferably provided with slots 22 disposed lengthwise of the plate to receive the screws 75 19, and for like reasons, the plate 18 is preferably provided with transverse slots 23 to receive the screws 20.

Explanation of the previous statement that the door 4 is by my device made pendulous from the supporting-frame-piece 1, whether the same be disposed above or below the door, is here offered. If the said frame-piece 1 be disposed above the door, as shown, for example, in Fig. I, the door hangs from 80 the bars 7 and 8, being supported thereon from below by the links 5 and 6, respectively. By reversal of the mechanism, however, the member 1 is disposed below the door, and the weight of the door in such case hangs 90 from the links 5 and 6, that are then supported from below, respectively, by the bars 7 and 8.

By reason of the preferred disposition of the pivots 11 and 12 relatively to each other 95 and likewise the relative disposition of the pivots 15 and 16, the door, suspended in either manner described, is caused to travel in a substantially true straight line as often as power is applied to move it transversely 100 in one direction or the other, provided that guide-mechanism be employed to cause the pivots at the points of reflexion 9 and 10, respectively, to travel smoothly and truly in their respective orbits 25 and 26 that are 105 respectively concentric to the pivotal points 11 and 12.

The form of guide-mechanism, shown and described, and for which I express only a present preference, consists of extensions 27 and 28 of the bars 7 and 8, respectively. Those extensions are preferably made longitudinally coaxial with the said bars, respectively, or, if the bars be bent, with those ends thereof of which said extensions, respectively, are elongations. They are also preferably provided, respectively, near their ends, with pivot bolts 29 and 30, each having a head of which one, 31, is shown in Fig. II, by the aid of which they are respectively, 110 loosely secured to the door 4 by a suitable loose-pivot connecting mechanism consisting preferably of guide-ways 32 and 33, preferably provided, respectively, with longitudinally disposed slots 35 and 36 made to accommodate the shanks of the respective bolts 29 and 30, and to guide their movements derived from the movements of the extensions 27 and 28. It is a feature of my invention 115 that the slots 35 and 36 are straight-line 120 125 130 135 140 145 150 155 160 165 170 175 180 185 190 195 200 205 210 215 220 225 230 235 240 245 250 255 260 265 slots, through the employment of which that compactness of structure and mode of operation made available by my invention are in part attained. Reversibility of the slot and bolt connection whereby the slots would be carried on the bar extensions and the bolts fixed to the door may, of course, be inferred from the preferred arrangement just described.

Because of that reversibility of my device through which a door may be supported from above or below at pleasure, the members 7 and 8 have been hereinbefore referred to specifically as bars, but in that form of embodiment of my invention in which the guide-mechanism, as described in the last paragraph, is employed, the bars 7 and 8, being prolonged by their respective extensions 27 and 28, become, in effect, levers, and as such serve not only the required purpose of guide-mechanism for controlling the travel of the pivot points 9 and 10 in their respective orbits, but also, in addition to their guiding function strictly, afford support and steadiness of motion to the door through their connection therewith secured as by means of the pivot bolts 29 and 30 working in their respective guide-ways 32 and 33.

The foregoing description applies equally, and for the most part without change of reference numerals, to all the figures of the drawings. The special purpose of Fig. III, as compared with Fig. I, is to illustrate means for converting the movement of the door from the direction of a horizontal straight line to that of an inclined straight line, whereby the door may be made to close (or to open if that were desirable) by its own weight. The said result is effected by inclining the plate 18 from the horizontal position which it occupies in Fig. I to the inclined position which it occupies in Fig. III, and at the same time shifting the plate 17 in a horizontal direction so as operatively to accommodate to the changed position of the plate 18 the other elements of the mechanism.

The relative adjustments of the plates 17 and 18 may be accomplished by the resetting of the screws or bolts 19 and 20 if inserted through round holes in the plates after the manner indicated in Fig. III, but by making provision in the plates themselves for such adjustment, the adjustments may be effected by the loosening without resetting of the screws. For this purpose slots 22 and 23 in the plates 17 and 18, respectively, are provided. By aid of the slots 23 the plate 18 may be, upon loosening of the screws 20, inclined from the horizontal to any extent desired within the limits imposed by the lengths of the slots, and a proper correlative adjustment of the plate 17 may be effected by loosening the screws

19 and sliding the said plate upon its slots 22 longitudinally in a horizontal direction to a position operatively correspondent to the adjustment of the plate 18. When the adjustments are made the tightening again of the screws 19 and 20 serves to fix the plates 17 and 18 in place.

Fig. V serves to illustrate, among other things, the determination of the relationship of the various elements of the mechanism effected by relative disposition of the pivot points 11 and 12, and shows the extreme limit of separation available between those points. In that figure, for distinction, the plate corresponding to the plate 17 is indicated by the additional numeral 40, the remaining numerals remaining unchanged. It may be observed that when the pivot points 11 and 12 are separated to the extent shown in Fig. V upon the plate 40, the effect is to bring the slots 35 and 36 in vertical alinement as distinguished from the angularly disposed positions which a shorter distance of separation between the points 11 and 12 imposes upon those slots. At the same time the inequality of the distance between the points 11 and 12 and that between the points 15 and 16, as previously postulated, is maintained.

It is a fact that may be understood upon inspection of the several Figs. I, III and V, that the preponderant weight of the door is except at a single point of its travel supported exclusively by one or the other of the links 5 and 6, or the bars 7 and 8, as the case may be. The preponderant weight of the door passes during its travel back and forth from one support to another, for example, from one of said links to the other, and in passing converts the companion support, or that one which is relieved of the main load, into a brace which has the effect only of holding the door in equilibrium. Consequently the weight of the door is mainly supported at all times upon a minimum number of pivotal connections as compared to the number which is called into requisition whenever the weight is equally distributed between both the supports or links 5 and 6, and which occurs in what may be denominated a "neutral field" of the door's travel. The effect is, mainly by the reduction of friction and the elimination of that resistance to motion due to the opposition of forces through the working of one supporting member against the other, to minimize the force required to drive it in either direction along its entire travel, or from any point thereof as a starting point. By my invention, the "neutral field", within the meaning of that term above defined, is reduced to a single point, in contradistinction to a line or succession of points as it exists in the prior art.

The operation of my device may be clearly

understood, in view of the foregoing specification, from the following summary. The plates 18 and 17 or 40, as the case may be, having been properly adjusted and secured 5 in relative positions, and in reference to the guide-mechanism, the door is thereby made ready for service.

By the adjustment of the plate 18 to the horizontal position shown in Fig. I, for example, the heaviest door may be opened or closed, as required, by a light pull in the desired direction applied to a handle 41, which for operation of my device may be located at any point that may be found 10 convenient.

If the plate 18 be inclined as shown in Fig. III, the necessary correlative adjustments being made to correspond therewith, the door will rise to its highest point when 15 opened in response to a pull upon the handle 41, and when the handle is released will descend by gravity to a closed position or its lowest point of travel. As specified, the adjustment last referred to may be effected 20 so as to cause the door to descend from either end of its travel to the other, and thereby either to open or to close automatically. An important feature of my mechanism is found in the fact that the force 25 necessary to operate it is so small that it may be, in its self-actuating adjustment, driven to its highest position, ready, upon release, for descent, by the application of force, so very little greater than that which is necessary 30 to operate it in a horizontal line of travel, as to be, in practice, scarcely appreciable.

What I claim is:

1. A sliding door supporting device, comprising two long levers pivotally connected at one end to a framing, two short levers pivotally connected at one end to the opposite sides of the vertical center of the door, and at their opposite ends to intermediate 45 portions of the first mentioned levers, and guiding means for the free ends of each of the said first mentioned levers.

2. A sliding door supporting device, comprising two long levers pivotally connected at one end to a framing, two short levers pivotally connected at one end to the opposite sides of the vertical center of the door, and at their opposite ends to intermediate 50 portions of the first mentioned levers, and guiding means on opposite sides of the vertical center of the door and adjacent the edges thereof for the free ends of each of said first mentioned levers.

3. The combination with a door and its 55 supporting framing, of two pairs of reflexed door supporting members, the two members of each of said pairs being pivotally united to each other at their points of reflexion, one of the said members of each of said pairs being pivotally connected at

their free ends to the door on opposite sides of the vertical center thereof, the remaining member of each of said pairs being pivotally connected at one end to the framing, and guiding means for the other ends of 70 said last mentioned members.

4. The combination with a door and its supporting framing, of two pairs of reflexed door supporting members, the two members of each of said pairs being pivotally united 75 to each other at their points of reflexion, one of the said members of each of said pairs being pivotally connected at their free ends to the door on opposite sides of the vertical center thereof, the remaining member of each of said pairs being pivotally connected at one end to the framing, and guiding means for the other ends of 80 said last mentioned members located on opposite sides of the vertical center of the door and adjacent the opposite edges thereof whereby the door is equally balanced on opposite sides of 85 its vertical center.

5. A device for slidably supporting doors within their framing, comprising two pairs 90 of reflexed door supporting members, the members of each pair being of unequal lengths, means for pivotally connecting the members of each pair at their points of reflexion, the short members of each pair having their free ends pivotally connected to the door on opposite sides of the vertical center thereof, the long members of each 95 pair each having one end pivotally secured to the door framing, and guiding means for 100 the opposite ends of said long members.

6. The combination with a door and its supporting framing, of a pair of short levers pivotally secured at one end to the door on opposite sides of the vertical center 105 thereof, a pair of long levers pivotally connected to the framing, the pivotal points of said short and long levers lying in different horizontal planes, means pivotally connecting the free ends of the short levers to the 110 long levers intermediate the length thereof, and guiding means for the free ends of the long levers.

7. The combination with a door and its supporting framing, of a pair of short levers pivotally secured at one end to the door on opposite sides of the vertical center thereof, a pair of long levers pivotally connected to the framing, the pivotal points of said short and long levers lying in different horizontal planes, means pivotally connecting the free ends of the short levers to the long levers intermediate the lengths thereof, and guiding means secured to the door adjacent the opposite sides thereof for the free ends 125 of the long levers.

8. The combination with a door and its framing, of a pair of long supporting members, said long members being pivotally secured to the framing on opposite sides of 130

the vertical center of the door when in its mid position from open to closed position, a pair of short levers pivotally connected to the door on opposite sides of the vertical center thereof whereby the door is supported at all times from points intermediate the center and the edges to prevent sagging, and means pivotally connecting said long and short members.

10 9. The combination with a door and its framing, of a pair of long supporting members, said long members being pivotally secured to the framing on opposite sides of the vertical center of the door when in its mid position from open to closed position, a pair of short levers pivotally connected to the door on opposite sides of the vertical center thereof whereby the door is supported at all times from points intermediate the center and the edges to prevent sagging, means pivotally connecting said long and short members, and guiding means secured to the door adjacent the opposite edges thereof for distributing the weight of the door.

25 10. A door supporting device comprising two pairs of reflexed door supporting members of unequal lengths, means pivotally

connecting the members of each pair at their points of reflexion, a plate connecting the free ends of the short levers, and a plate connecting the corresponding ends of the long levers, said plates being provided with adjusting openings, the adjusting openings in one of the plates having their longitudinal axes extending at substantially right angles to those of the other plate.

11. A sliding door supporting device, comprising two long levers adapted to be pivotally connected at one end to a door framing, two short levers adapted to be pivotally connected at one end to the opposite sides of the vertical center of a door, and pivotally connected at their opposite ends to intermediate portions of the first mentioned levers, and guiding means for the free ends of each of said first mentioned levers.

In testimony whereof, I have hereunto set my hand in the presence of two subscribing witnesses.

ANDREW F. LARSON.
